UNITED STATES PATENT OFFICE.

ERNEST FOURNEAU, OF PARIS, FRANCE.

PROCESS OF PRODUCING AMINO-ALKYLESTERS.

No. 829,374.

Specification of Letters Patent.

Patented Aug. 21, 1906.

Application filed June 3, 1905. Serial No. 263,637.

To all whom it may concern:

Be it known that I, ERNEST FOURNEAU, a citizen of the Republic of France, and a resident of Paris, France, have invented an Improved Process for Producing Amino-Alkylesters, of which the following is a specification.

This invention consists of a process for producing amino-alkylesters of the combination

15 In my patent application Serial No. 199,283 it was shown that by the action of aliphatic amines on halogen hydrins of the formula

20 (R₁ and R₂=alkyl or aryl or aralkyl, x=halogen) or by the action of magnesium organic compounds—for instance, alkyl mg. halogen on amino acetones or ester of an amino acid with tertiary amino group—there are formed amino alcohols of the combination

25 (R₁ and R₂=alkyl or aryl or aralkyl, R₃ and R₄=alkyl or hydrogen.)

30 The word "aralkyl," which is quite commonly employed, is a combination of the two words "aryl" and "alkyl." The word "aryl" is applied to the radicals of the aromatic series—for example, C₆H₅; the word "alkyl" to the radicals of the greasy or aliphatic series—for example, CH₃ . . . C_nH_{2n+1}. The word "aralkyl" designates, therefore, every radical of the one or the other series.

35 The present process relates to the production of acidulated derivatives of the amino

alcohols described in the application Serial No. 199,283 of the combination

(R=acidyl; R₁ and R₂=alkyl or aryl or aralkyl; R₃ and R₄=alkyl or hydrogen.)

Since the introduction of cocaine in surgery numerous attempts have been made to obtain a product which possesses the same physical properties as cocaine and is as effective as this, but less toxic (poisonous) and cheaper.

In studying the physiological influence of the groups characterizing cocaine it was established that its anesthetizing effect is not unconditionally connected with the presence of the atom complex COO.CH₃. Thus, for instance, the benzoyl derivative of alpha-tropin—i. e., tropacocaine—itself acts as an analgesic (locally anesthetizing) to a high degree. This is the case also with beta-eucain, a chlorhydrate of the benzoylvinylidiaceton-alkamin, which contains no carboxyl group, as opposed to alpha-eucain, which for its part shows the three characterizing groups of cocaine. Thus the properties of these bodies to be able to act as local anesthetics appears to be dependent on the presence of the two groups—namely, first, a secondary or tertiary amino group; second, a tertiary alcohol group, which has been treated by any desired aromatic acid. However, with respect to the locally-anesthetizing properties only such alcohols have been hitherto more closely examined as are derived from piperidin, (eucain and tropa-cocaine.) The influence of the piperidin residue on the toxicity of these compounds is known. Now it was found that, first, the acidulated derivatives of most of the amino alcohols possess locally anesthetizing properties; second, the presence of piperidin residue is not necessary therefor; third, that these properties seem to reach their highest point when the alcohol group is a tertiary one and the amino group is near to the alcohol group.

100

The amino alcohols of the above-cited compounds or their ester possess strong and lasting local anesthetizing properties. They are almost non-poisonous, and their physical properties make them very suitable for use in therapeutics. Their salts are easily soluble in water. An injection of the watery solution does not incite pain, and these solutions, even after long boiling, are entirely stable.

The production of the acidulated derivatives (ester) takes place according to the usual methods employed in similar cases. First. By treating the amino alcohols obtainable according to application Serial No. 199,283 with an acid chlorid. (Compare Berthelot, *C. R. Ac. D. Sc.*, 73, p. 493; Schotten-Baumann, *Berichte*, Vol. 17, p. 2445; 19, p. 3219; (a) in the presence of pyridin (Einhorn *Liebig's Annalen*, 301, 7; (b) in simple manner by mixing the acid chlorid in question with the amino alcohol in etheric or benzolic solution. Second. By treating the base in benzolic solution with benzolacid-anhydrid, (Willstätter.)

Examples.

1. From dimethylaminotrimethylbenzoylcarbinol:

One hundred grams of dimethylaminotrimethylcarbinol (of point of boiling 60° under forth-eight millimeters pressure) are dissolved in two hundred grams of benzoyl chlorid, which is for its part dissolved in the same quantity, by weight, of benzol. The mixture at first remains as light as water and becomes heated to a considerable degree. Then the whole suddenly passes over into the solid aggregate condition, and a crystalline mass results. After cooling, this is thrown out, then repeatedly washed with benzol, and the mass is recrystallized out of absolute alcohol. The yield is almost theoretical. The hydrochlorate of the dimethylaminotrimethylbenzoylcarbinol recrystallizes out of absolute alcohol in beautiful transparent cubes, which decompose in the air. These are very easily soluble in water, as well as in warm methyl alcohol, but almost insoluble in acetone, and melt at 202°.

2. From dimethylaminodimethylphenylbenzoylcarbinol:

Fifty grams of dimethylaminodimethyl-phenylcarbinol (which boils at 147° to 149° under twenty-four millimeters pressure) are mixed with one liter of normal solution of caustic soda. Thereupon one hundred 70 grams of benzoyl chlorid are added, drop by drop, to the cooled-off mass and the whole is vigorously shaken. The dropping in of the benzoyl chlorid is continued about two hours. Thereupon the mass is shaken for another 75 hour, and it is determined from time to time whether the mixture still shows a decided alkaline reaction. Then the mass is lixiviated with benzol. The solution of benzol is carefully dried with heated sulfate of soda, 80 and the benzoyl derivative is precipitated as hydrochlorate by means of an etheric solution of hydrochloric acid. Thereupon the chlorhydrate is washed out with benzol and then dissolved in warmth in absolute alcohol. 85 On cooling, the salt crystallizes in the form of extensive shining plates, which are but slightly soluble in water and melt at 206°.

3. From dimethylaminodimethylethyl- 90 benzoylcarbinol:

The corresponding amino alcohol boils at 57° under twenty-three millimeters pressure and at about 140° at ordinary atmospheric pressure.

The benzoyl derivative is liquid and boils without decomposition at 149° under twenty-five millimeters pressure. The chlorhydrate ¹⁰⁵ crystallizes out of absolute alcohol in very fine needles or shining leaflets, which are very easily soluble in water, but very slightly soluble, on the other hand, in cold acetone. It furthermore dissolves very well in methyl alcohol. The body melts at 175° . The oxalate, crystallizing in the form of fine needles, melts at 145° . ¹¹⁰

4. From dimethylaminodimethylpropylbenzoylcarbinol: 115

The corresponding amino alcohol boils at 78° under thirty-five millimeters pressure. ¹²⁵
The benzoylchlorhydrate is very easily soluble in water, alcohol, and acetic-acid ester. It crystallizes out of an alcohol-ether mixture in small very hygroscopic needles, which melt at 146°. ¹²⁶

5. From dimethylaminodimethylisoamylbenzoylcarbinol:

¹⁰ The corresponding amino alcohol boils at 98° to 99° under twenty-four millimeters pressure.

15 The benzoylchlorhydrate crystallizes out of an alcohol-ether mixture in fine long silk-like needles which melt at 138° . It is very easily soluble in water and alcohol, but almost insoluble in boiling acetone. Its taste is very bitter and biting. The platino-chlorid salt melts at 178° without decomposition.

20 6. From dimethylaminomethyldiethylbenzoylcarbinol:

The corresponding amino alcohol melts at 76° to 79° under twenty-three millimeters pressure. The benzoylchlorhydrate melts at 189° and crystallizes out of absolute alcohol in fine shining prisms.

7. From dimethylaminodimethylbenzylbenzoylcarbinol:

The corresponding amino alcohol boils at 144° under twenty-four millimeters pressure. The benzoylchlorhydrate crystallizes out of methyl alcohol in beautiful shining and large 45 crystals which melt at 195° . It is very easily soluble in boiling absolute alcohol and crystallizes out of the latter in fine needles which are pretty soluble in water.

In the following there are cited some examples for the production of other acidulated amino alcohols—namely, cinnamyl-isocaleryl and acetyl derivatives. The production of these bodies corresponds, essentially, to that of the benzoyl derivatives.

55 8. From dimethylaminotrimethylcinnamylcarbinolchlorhydrate:

This body is obtained by dissolving one 65 part, by weight, of cinnamic-acid chlorid in

four parts, by weight, of benzol, and, on the other hand, one part, by weight, of the dimethylaminotrimethylcarbinol in four parts, by weight, of benzol and mixing them together. The mixture is at first clear as water, soon becomes greatly heated, whereupon after a short time the cinnamylchlorhydrate is precipitated in a quantity approximately corresponding to the theoretical quantity. The product is thrown out and recrystallized out of absolute alcohol. Thus crystals are obtained in the form of large tablets, which are pretty soluble in warm absolute alcohol, but less soluble, on the other hand, in cold alcohol. The body, besides, is soluble in acetone. Its melting-point lies at 208°. 70 75 80

The chlorhydrates of the cinnamyl derivative described further on, as well as those of the isovaleryl derivatives, are produced in the same manner. 85

9. From dimethylaminotrimethylisovalerycarbinolchlorhydrate:

The production of this body corresponds to that of the preceding one, only isovaleryl chlorid must be used in place of the cinnamic-acid chlorid. You obtain large leaflets, which are fatty to the touch and have a bitter and fresh taste, as well as a slight odor. The body dissolves very well in most of the solvents, with the exception of cold benzin and ether. The compound melts at 112° , 105 but in very imperfect manner.

10. From dimethylaminodimethylmethylethyl-isovalerylcarbinolchlorhydrate. This body is obtained in the same manner as the preceding one and crystallizes in the form of large leaflets ¹¹⁰ fatty to the touch. The physical properties of the product correspond to those of the preceding body. It possesses a fresh taste, has a slightly-anesthetizing effect,

softens at 120° , and melts completely at 150° . 115
11. From dimethylaminodimethylcinnamylcarbinolchlorhydrate. This body is obtained by dissolving equal parts, in weight, of the corresponding amino alcohol and of cinnamic-acid chlorid in benzol. 120

The body may be recrystallized out of alcohol mixed with ether and then yields shining leaflets. The product has a very bitter taste and strong anesthetizing action. It is pretty soluble in absolute alcohol, very easily 125 soluble in water, and melts at 203°.

12. From dimethylaminomethylisobutylcinnamylcarbinolchlorhydrate. The production of this body corresponds to that of the preceding one. It consists of large leaf- 130

lets which are easily soluble in alcohol and acetone. The compound is recrystallized out of an alcohol-ether mixture and then melts at 185°.

5 13. From dimethylaminodimethylisoamyl-
cinnamylcarbinolchlorhydrate. This body is
obtained in a like manner as the previously-
described substances and crystallizes out of a
mixture which consists of acetone and ether
10 free from water in fine prismatic needles
which melt at 104°.

14. From dimethylaminodimethylbenzyl-cinnamylcarbinolchlorhydrate. This product is obtained by dissolving the corresponding benzyl base and cinnamic-acid chlorid in benzol. Small light leaflets are formed which are very easily soluble in alcohol and acetone. The melting-point lies at 150°.

15. From dimethylaminodimethylphenyl-
20 isovalerylcarbinolchlorhydrate:

30 Like parts in weight of the corresponding amino alcohol and of isovaleryl chlorid are dissolved in benzol. Herewith a lively heating ensues. After the mass grows cold the final product crystallizes out in fine needles.

35 The same is soluble in nearly all solvents and may be recrystallized by means of an alcohol-ether mixture. Thus one obtains fine shining needles which have a faint odor and melt at 180°

40 16. From diethylcarbaminacidester of the dimethylaminodimethylmethylethylcarbinolchlorhydrate:

The body is obtained by heating like parts, in weight, of diethylcarbamin-acid chlorid

and dimethylaminodimethylethylcarbinol without a solvent for one day in a boiling-water bath. The sticky mass is treated with ether and mixed with carbonate of sodium. Then the mass is again extracted with ether, and the etheric solution after it has been well

dried out by means of heated carbonate of potassium is distilled off. The residuum is fractionated *in vacuo* and the base drawn off at 135° to 140° under forty-one millimeters pressure. The base thus obtained is changed into the chlorhydrate by dissolving gaseous hydrochloric acid in ether free from water and mixing it with the base. The chlorhydrate is precipitated and may be recrystallized out of a mixture of alcohol and ether free from water. You obtain fine shining needles or leaflets which are soluble in most solvents and melt at 144° with simultaneous decomposition.

17. From dimethylaminodimethylethyl-acetylcarbinol:

The corresponding carbinol is heated with the double, part, in weight of acetic-acid anhydrid for about four hours to 120°. The product of action is treated with water and sodium carbonate and then extracted with ether. The free ester boils at 80° to 85° under thirty-two millimeters pressure. It has a slight odor of acetic acid and rapidly colors in the air with simultaneous decomposition.

18. From dimethylaminodimethylethyl-
isovalerylcarbinol. The production of this
compound corresponds to the ester spoken
of in the preceding example. It has a strong
smell of herring. The product is clear as
water and boils without decomposition at 128°
under thirty-two millimeters pressure. 95 100

I claim as my invention—

The process for the production of amino-alkylesters of the formula

substantially as described, which process consists in acidulating amino alcohols containing a tertiary alcohol group and an amino group and thereby obtaining acidulated derivatives. 115

In testimony whereof I have signed my name to this specification in the presence of two subscribing witnesses.
